United States Patent Office.

CHARLES A. MAXFIELD, OF NEW YORK, N. Y.

Letters Patent No. 77,502, dated May 5, 1868; antedated April 23, 1868.

IMPROVED MACHINE FOR FORMING PASTEBOARD BOXES.

The Schedule referred to in these Letters Patent and making part of the same.

TO ALL WHOM IT MAY CONCERN:

Be it known that I, CHARLES A. MAXFIELD, of the city and State of New York, have invented, made, and applied to use a certain new and useful Improvement in Machine for Folding Boxes and Box-Envelopes; and I do hereby declare the following to be a full, clear, and exact description of the said invention, reference being had to the annexed drawing, making part of this specification, wherein—

Figure 1 is a vertical section of the said machine through the folding-die.

Figure 2 is a sectional plan, showing the bed, with the sheet of paper to form the box shown in red lines, and the plunger or former in blue lines.

Figures 3, 4, and 5 are perspective views of the folded box in its various stages.

Similar marks of reference denote the same parts.

The object of my invention is to fold up into the shape of a box, a sheet of paper or other material, previously cut out to shape, and to effect this operation, with great rapidity and precision, so that box-envelopes, paper boxes, and a variety of box-shaped bags, of any desired size and character, can be folded with but little cost.

My invention consists in a series of folders, combined with a former in such a manner that the sheet of material is folded against and wrapped around said former, the parts acting successively as the plunger is forced into a die containing these folders, and carries the paper or other material with it, delivering the same in the form of a folded box or box-envelope.

In the drawing, *a* is a bed, with standards, *b b*, in which is fitted to slide the head-block, with its plunger, *c*, the sides of which are parallel or nearly so, and of a size corresponding to the interior of the box to be formed. This plunger hence becomes a former, and it is actuated by a lever, *d*, or other convenient means.

The bed *a* has an opening through it, and the edges *2 2* thereof form the first fold of the paper or other material as the plunger is brought down upon it, carrying the same in between the edges *2 2*.

In fig. 2, the red lines show the shape of the box-material as cut out to shape, and laid down to its position within the gauge or fence, *e*.

f and *g* form the sides of the box, *h h* the first folded portion of the sides, *i i* the second portion of the sides, that extends from the bottom, *k*, of the box, and *l l* the portion of the sides last folded. The interior surfaces of the portions *i i* and *l l* should be covered with glue, or other adhesive material, so as to unite with the surfaces into which they are turned into contact.

In the manufacture of box-envelopes, the folding-flap, *m*, and corner-pieces, *n*, are also provided. They are to be creased and folded at the dotted lines, shown in figs. 3, 4, and 5, so as to complete the cover or flap of the box-envelope. This feature, however, forms no part of my present invention, as the box may be formed of any desired shape, either with or without the cover or flap.

As the plunger descends, and the edges *2 2* fold up the sides *f g*, the further descent of the former, *c*, brings the material in contact with a stationary folding-stud, *3*, that folds in the side-pieces *h* towards and upon the former, *c*, then the parts *i i* are turned up, as seen in fig. 4, against the side-pieces *h*, by coming in contact with the second set of folders *4 4* and so on, the last fold of the side-pieces *l l* is made by the folders *5 5*.

The edges of these folders *3*, *4*, and *5* are to be rounded, so as not to cut the paper or other material, and they may be adjustable, so as to suit different thicknesses of material or sizes of box.

The gauge or fence *e* may be shaped so as to receive the flap of the box-envelope, shown in fig. 2 by red lines.

The box is carried through the die formed of said folders, and taken by a suitable device, and the former, *c*, draws up out of it.

What I claim, and desire to secure by Letters Patent, is—

The former, *c*, in combination with the folders *2 3 4 5*, substantially as specified, so that the folding of a box or box-envelope is effected by driving the previously-cut sheet of material through between said folders, as set forth.

In witness whereof, I have hereunto set my signature, this 29th day of July, A. D. 1867.

CHAS. A. MAXFIELD.
